B. LACKEY.

NUT LOCK.

APPLICATION FILED APR. 18, 1912.

1,077,412.

Patented Nov. 4, 1913.

UNITED STATES PATENT OFFICE.

BEN LACKEY, OF MERIDIAN, MISSISSIPPI.

NUT-LOCK.

1,077,412.

Specification of Letters Patent.

Patented Nov. 4, 1913.

Application filed April 18, 1912. Serial No. 691,598.

To all whom it may concern:

Be it known that I, BEN LACKEY, a citizen of the United States, residing at Meridian, in the county of Lauderdale and State 5 of Mississippi, have invented certain new and useful Improvements in Nut-Locks, of which the following is a specification.

My invention relates to improvements in means for locking nuts against movement 10 upon their bolts, and the object of my invention is to provide a device by means of which the nuts may be quickly locked in place and which will at the same time permit the ready unlocking of the nuts when desired.

15 A further object of my invention is to provide a device which may be employed in locking the nuts upon a plurality of aligned bolts and which is therefore especially applicable in the bolting of rail joints. And a 20 still further object of my invention is to provide a pivoted bar which, in adjusted position, extends adjacent the peripheral faces of the nuts to prevent their turning and which is secured in this position by a 25 key operated lock, the employment of a key preventing accidental loosening of the device.

With these and other objects in view, my invention will be more fully described, illustrated in the accompanying drawings, and then specifically pointed out in the claims which are attached to and form a part of this application.

In the accompanying drawings: Figure 1 25 is a perspective of a rail joint, showing my improved locking device applied thereto; Fig. 2 is a side elevation of the same, partially in section to more clearly show the construction of the lock; Fig. 3 is a transverse 40 section taken through the stop pin of the locking device and looking toward the pivotal end of the locking bar thereof. Fig. 4 is a detail perspective of one end of the pivoted bar and the lock carried thereby.

45 Corresponding and like parts are referred to in the following description and indicated in all the views of the drawing by the same reference characters.

My present invention embodies the application 50 of the locking bar 10 to one of the fish plates of a rail joint designated as a whole by the numeral 11. The abutting ends of the rails 12 and 13 are secured end to end by means of fish plates 14 and 15 which bear 55 against the opposite web portions of the rails and have their upper edges shaped to

conform to the lower face of the head of the rails as shown at 16. These fish plates, at their lower edges, are provided with outwardly directed extensions 17 which bear 60 upon the rail flanges, and base plates 18 are formed integrally with these extensions and engage beneath the flanges. As will be readily seen this manner of constructing the fish plate and base plate in a single piece gives 65 great additional strength to the joint.

The fish plates are provided with a plurality of spaced apart, correspondingly positioned bolt receiving bores and the web portions of the adjacent rail ends are correspondingly bored to receive a plurality of bolts 19 which are passed through both fish plates and the web of the rail and secured by nuts 20 which are turned firmly home against the outer face of the fish plate 75

14. To prevent disengagement of these nuts from their bolts is the primary object of my invention and I accomplish this by the employment of the bar 10 which is provided at one end with an enlarged, perforated head 80 21 which is swingingly mounted upon a pin 22, the inner end of which is passed through the fish plate 14 and secured against disengagement by heading or other preferred means. In operative position, this bar 10 85 extends longitudinally of the fish plate and bears upon or extends just above the upper faces of the nuts and it will therefore be understood that as long as the bar is maintained in this position, each and every one 90 of the nuts will be held against turning upon the bolts. In order to limit the downward swinging of this bar and for another purpose which will be hereinafter explained, I have provided a pin 23, one end of which is 95 secured in the fish plate 14 and the other end of which extends outwardly to engage the locking bar 10 when the latter is swung to position. The upper face of this pin is preferably cut-away to form a seat 24 for the 100 reception of the locking bar and a resultant shoulder 25 to hold the free end of the locking bar against any possible outward movement. The under face of the locking bar, adjacent its free end, is also preferably provided with a transversely extending channel 26 for the reception of the pin 23 when the bar is in lowered position.

As a means for locking the bar in lowered or operative position, I have provided a substantially rectangular shaped casing 27 110 which is secured against the lower face of

the free end of the bar by a pin or rivet 28 at its rear end and a metallic strap 29 at its forward end, this strap passing around the forward end of the casing and the locking bar and securing the two firmly together. This casing incloses a lock, designated as a whole by the numeral 30 and including the longitudinally movable bolt 31 having a terminal 32 which in the outer 5 position of the bolt engages beneath the pin 23. The movement of the bolt within its casing is limited by means of a pin 33 which extends transversely through the casing and through a suitable transverse slot 34 formed 10 in the lower face of the bolt. A helical spring 35 serves to normally maintain the bolt in extended position, one end of this spring being adapted to engage against the wall of the casing and its opposite end being 15 adapted to bear against the vertical rear face 36 of the bolt.

Both of the side walls of the casing are provided in their upper edges with slots 38 which register with a transversely extending slot 39 formed in the upper face of the bolt 31 when the latter is in extended position and the locking bar 10 is provided in its lower face with a transversely extending slot 40 which is in alinement with the slots 30 38 of the casing. The slot 40, together with the slots 38 form a key receiving opening into which a key may be inserted to bring its ward into engagement with the slot 39 of the bolt, when a clockwise turning of the 35 key will retract the bolt against the action of the spring 35 to release the locking lever.

The lower face of the extension 32 of the bolt is preferably beveled in such a manner that when the locking bar is swung down 40 to operative position, this beveled face will engage against the pin 23, causing the bolt to be forced back until the locking bar is in place when it will immediately spring out to normal position to engage beneath 45 the pin 23.

From the foregoing description, taken in connection with the drawings, the operation

of my improved lock will be readily understood and any further description of the same is therefore unnecessary. 50

It will of course be understood that the locking bar and lock casing, while preferably formed of metal, may be made of wood or other material if desired.

Having thus described the invention, what 55 is claimed as new is:

1. The combination with a fish plate having a plurality of alined bolt receiving apertures, of a bar pivoted by one end to the plate and movable into parallel spaced relation to the line of the apertures, a pin extending from the fish plate in position to support the bar, a casing secured to the lower face of the bar, a spring pressed bolt 60 slidable in said casing and adapted in extended position to engage beneath the pin and lock the bar thereto, and key operable means for retracting said bolt. 65

2. The combination with a fish plate having a plurality of alined bolt receiving apertures, of a bar pivoted at one end to the fish plate and movable into parallel spaced relation to the line of the apertures, the free end of the bar being cut-away transversely to provide a seat, a pin extending from the 70 fish plate in position to engage in said seat when the bar is in locking position and hold the latter against further downward movement, said pin being cut-away to receive the bar and to provide a terminal shoulder engaging the outer face of the bar to hold the same against outward swinging movement, a casing secured to the bar; and a spring 75 pressed normally extended bolt movable in the casing and adapted to engage beneath the pin to lock the bar against upward swinging movement. 80

In testimony whereof I affix my signature in presence of two witnesses.

BEN LACKEY. [L. s.]
